ROBERT G. ELLIS, OF UNIVERSITY, MISSOURI, ASSIGNOR TO AMERICAN CAR AND FOUNDRY COMPANY, OF ST. LOUIS, MISSOURI, A CORPORATION OF NEW JERSEY.

DRAFT-ARM AND CENTER-SILL REINFORCEMENT FOR UNDERFRAMES.

1,224,866.

Specification of Letters Patent.

Patented May 1, 1917.

Application filed May 16, 1916. Serial No. 97,841.

To all whom it may concern:

Be it known that I, ROBERT G. ELLIS, residing at University city, St. Louis county, Missouri, and being a citizen of the United States, have invented certain new and useful Improvements in Draft-Arms and Center-Sill Reinforcements for Underframes, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

20 Fig. 1 is a plan view of somewhat less than half of an underframe in which my draft arm and center sill reinforcement is incorporated, the remainder of said underframe being constructed substantially in accordance with what is shown in the illustrated portion and the draft arm being oppositely directed;

Fig. 2 is a central vertical longitudinal section of the construction shown in Fig. 1;

30 Fig. 3 is a transverse section through the center sills and the draft arm and center sill reinforcement, being taken on line 3—3 of Fig. 2 and viewed in the direction of the arrows;

35 Fig. 4 is another transverse view through the center sills and draft arm and is taken on the line 4—4 of Fig. 2 looking in the opposite direction;

40 Fig. 5 is a fragmentary half-plan view of a modified form of my draft arm and center sill reinforcement;

Fig. 6 is a central vertical longitudinal section of the parts shown in Fig. 5; and

45 Fig. 7 is a transverse section of another modification showing the draft arm in combination with a single girder serving as the center sill reinforcement.

The present invention relates to a draft arm and center sill reinforcement and has for an object an efficient draft arm at each end of a railway car. A center sill reinforcement so associated with the draft arms and with the usual car underframe that an appropriately rigid buffing-column results,

capable of resisting heavy coupling shocks, 55 is contemplated.

Another object is to so construct the draft arm and center sill reinforcement that it shall be readily applicable either to old or new cars. Its use in connection with the 60 cars of the earlier types, which have already given long service, and the wooden underframes of which were designed in times prior to the advent of long trains composed of heavy steel rolling stock and ponderous 65 motive units, adapts the older cars to safe usage in conjunction with the more modern cars built for more severe railway operating conditions.

Referring to the drawing, the draft arm 70 is pressed from a single rectangular plate, and it is to be understood that said draft arm, the end sill, bolster, etc., are to be duplicated at each end of the car.

For convenience of description that portion of the draft arm intermediate the bolster and the next adjacent end sill is herein-after referred to as the outer end and the portion thereof from the forward edge of the bolster to the end intermediate the bol- 80 sters is referred to as the inner end.

In the drawing, the horizontal web 1 of the draft arm is continuous from the inner end of said arm to the end sill A, as indicated in Figs. 1 and 2.

B indicates the usual body bolster and C the usual wood center sills still found in many old cars remaining in service.

The inner end of the draft arm comprises the web 1 before referred to employed as a 90 connector for two spaced and relatively U-shaped center sill embracing portions D—D, each of which includes a vertical portion 2, a horizontal seat 7, upon which rests a wood sill C and a second vertical portion 8 paralleling the vertical portion 2.

The vertical draft arm portions 2 and 8, respectively on the inner and outer faces of the wood sills C, with the portions 7 forming longitudinal pockets into which are received said wood center sills.

Beginning approximately at the longitudinal median line of the bolsters B; the web 1 of each draft arm slopes downward as it extends inwardly from the car end it is 105 associated with. At the lower termination of the slope, said web again becomes horizontally disposed in a lower plane. As well

illustrated in Fig. 3, the inverted U-shaped inner end of each draft arm, which is existent between pockets D—D and comprises web 1 and the inner vertical pocket walls 5 2—2, has a contour admirably adapted to receive the end portions of the sub-sills 11. Said sub-sills 11 may be the commercial Z-bars shown, or any other suitable longitudinal members. Their end portions project 10 into the central inverted U-shaped portion of the inner end of each draft arm, the bottom out-turned flanges of the Z-bars having their end portions underlying and stiffening the horizontal portions 7 of the draft arm 15 pockets D—D.

Between the draft arms at opposite ends of the car, the bottom flanges of the Z-shaped sub-sills 11 stiffen the wood center sills C—C, as do the webs of the Z-bars lying 20 against the inner vertical faces of said wood center sills. Bolts F pass horizontally through the vertical webs of sub-sills 11 and the wood center sills, firmly uniting the same. The Z-bars 11 consequently are reinforcements for the original wood sills, giving them adequate strength to sustain any stresses they may be subjected to in service.

The top flanges of the Z-bar sub-sills 11 are inwardly directed and are joined by a 30 connecting or cover plate P, secured thereto by rivets 15, or other fastening means. Thus, a channeled or inverted U-shaped center sill reinforcement is created and provided with outstanding center sill-stiffening flanges.

The lower horizontal portion of the inner end of the web of each draft arm lies upon cover plate P, and is secured thereto by those of rivets 15 which pass through the top 40 flanges of the end portions of the Z-bars that are embraced by the central inverted U-shaped portions of inner end of the draft arm. Within the lapping portions of the sub-sills 11, cover plate P and the inner end 45 of the draft arm webs 1, rivets 15 are more closely spaced to improve the strength of the connection between these parts.

The lower outstanding flanges of the center sill-reinforcing sub-sills 11 are riveted 50 at 16 to the horizontal portions 7 of the pockets D at the inner end of each draft arm.

At each bolster, the draft arm is secured thereto by vertical bolts 17, which pass 55 through the bolster B, the horizontal portion 7 of each pocket D and through the wood center sills C seated in said pockets.

Near the outer edges of the bolsters B, the contour of the webs 2 of the draft arm is 60 modified. Said webs gradually increase in depth, as indicated by the line K in Fig. 2, and the outer ends of the draft arm pocket portions are of modified contour, as also shown in said Fig. 2 and in the sectional 65 view of Fig. 4.

Thus the draft arm is formed, within the zone of the draft lugs L, of sufficient depth, to not only connect with the center sills and connect said sills to prevent spreading during buffing, but also to support standard draft lugs adapted to receive well known types of draft gears.

The lug L shown is that of my Patent 1,042,416 of October 29, 1912, which is of a well known type and requires no further description.

Intermediate the web portions 2 and the lower and more widely spaced portions 2^a thereof are shoulders 5, which are accommodated by cutting out a corner portion of the 80 wood center sills as shown in Fig. 4.

The lower parts of the web portions 2^a terminate in horizontal outstanding flanges 6, which, with the web portions 2^a and shoulders 5, form oppositely disposed Z-shaped 85 draft sills, which are properly spaced to receive standard draft gears and which are rigidly connected together and to the center sill end portions through the inverted U-shaped formation comprising the web 1 and 90 inner vertical walls 2—2 of the center sill pockets aforementioned.

Horizontal bolts E extend through the just mentioned vertical portions 2—2 and the end portions of wood center sills C—C, and 95 are of such number as are required to properly unite the parts indicated.

The lower portions 2^a of the inner vertical walls 2 of each draft arm project outwardly beyond the outer ends of the upper portions 100 of walls 2 and the outer end of the web 1, continuing beyond the outer face of the end sill A, and being connected, as by rivets, to a striking plate casting S. Said lower portions 2^a are also connected to end sill A by 105 connection angles 12 riveted to the outer faces of each of said portions 2^a. A horizontal flange of each connection angle 12 is secured to the end sill A by a vertical bolt 13 passing through both said flange and end 110 sill.

From the foregoing, it is to be seen that the draft arms at opposite ends of the car are connected by center sills suitably spaced apart, and also by the center sill reinforcement comprising the Z-shaped sub-sills 11 and cover plate P. Center sills C are also coupled with each other by the web 1 and the metal of the pockets D of the unitary draft arms. Hence, a sufficiently rigid buffing column is formed adapted to resist coupling shocks.

If, in extreme cases, due to age or other causes, the center sills C should further fail, the center sill reinforcement will still maintain a strong connection between the draft arms and will preserve the buffing column sufficiently well to prevent wreckage until repairs can be made.

In the preferred form of said column the 130

spaced center sills of wood are securely connected from the end sills to a considerable distance intermediate the bolsters by means of relatively inflexible materials which pocket and stiffen said center sills within the portions thereof which necessarily receive the major buffing stresses, while preserving the elasticity of the wood members intermediate the bolsters to absorb minor stresses by less frequent connections between the center sills and the center sill reinforcement.

If it be desired to connect the draft arms by more rigid means, a single girder as 20, shown in Fig. 7, may be employed extending from bolster to bolster in which case the brackets 23 riveted respectively to the horizontal portions 7 of the draft arms and to the web of such girder, will form a suitable connection, and brackets 23 will form supports for the old wood center sills which should be secured to the draft arms and to said brackets.

Figs. 5 and 6 illustrate a modified form of connection between the inner end of the draft arm and the center sill reinforcement comprising the sub-sills 11 and the cover plate P. Web 1^a at the inner end of the draft arm is not deflected downward, thus saving the operation necessary to reduce the height of the inner ends of the draft arms of the first described form.

The parts of the modified structure of Figs. 5 and 6 correspond to those illustrated in Figs. 1 to 4 inclusive, except as to the inner ends of the draft arms and the addition of rivets 19, and these similar parts bear similar reference characters.

In Figs. 5 and 6, web 1^a of the draft arms extends to its rear end without being depressed to lie upon cover plate P, being spaced above the latter. Connection between the draft arm and the center sill reinforcement, comprising the shaped sub-sills 11 and cover plate P, is made by rivets 19 arranged in horizontal rows, those of each row passing through the vertical web of one of the Z-bars 11 and the inner vertical wall 2 of the pocket D of the draft arm that is adjacent that Z-bar.

In Figs. 1 and 2, a tie-plate H, riveted to the under faces of the horizontal portions 7 of the spaced pockets D of each draft arm, is seen to abut an inner upper edge of the contiguous bolster B. As there is a tie-plate H similarly arranged adjacent each bolster, any tendency of either draft arm, the arms being connected by the center sill reinforcement, to creep relatively farther rearwardly of its associated bolster is overcome. For example, if an impact is received by the draft arm at one end of the car, it will be transmitted through the center sill reinforcement to the draft arm at the opposite end of the car. Tie-plate H

carried by the latter draft arm abuts the adjacent bolster and prevents longitudinal movement of the center sill reinforcement, which, being rigidly connected with the draft arm that received the impact, prevents the same creeping farther toward its affiliated bolster. Tie-plates H may be on both sides of each bolster, if desired, and those adjoining the sloping side K of the draft arms may be bent to conform to such sides.

What I claim is:

1. In combination in a car underframe provided with end sills and center sills, draft arms held adjacent the end sills and comprising alternately reversing channel portions in some of which opposite end portions of the center sills lie and are securely affixed, and a reinforcement for the center sills extending between and rigidly connecting the draft arms.

2. In combination in a car underframe provided with end sills and a center sill, draft arms projecting inwardly from the end sills and provided with seats partly U-shaped and altering to have different form, opposite ends of the center sill being retained by said seats and held thereby against transverse displacement, and means connecting said center sill and draft arms.

3. In combination in a car underframe having end sills and spaced center sills, draft arms projecting inwardly from the end sills and each comprising spaced pocket portions in part embracing opposed sides of corresponding end portions of each of said spaced center sills and elsewhere embracing only adjacent sides thereof, and other portions preventing the spreading of said pocket portions, and means securely attaching said center sills and draft arms together, said center sills connecting said draft arms.

4. In combination in an underframe, for railway cars having an end sill, a bolster and spaced center sills, a draft arm comprising spaced pocket portions fitted to the sectional shape of and embracing a greater and lesser number of sides of portions of said center sills in different parts of said pocket portions, a portion tying said pocket portions against lateral displacement, and other depending portions extending between said end sills and bolster adapted to support draft gear elements, and means rigidly securing said center sills to said draft arm.

5. In combination in a railway car underframe having an end sill, a bolster, spaced center sills and a striking plate, a draft arm comprising spaced U-shaped pocket-forming portions in which end portions of said center sills lie, a portion preserving the alignment of said pocket forming portions and depending draft sill portions extending forwardly from said bolster, under said end sill and connected to said striking plate,

- and means connecting said center sills and draft arm.
6. In a car underframe having spaced center sills, a draft arm comprising a central portion of inverted U-shaped section and portions on opposite sides of said central portion fashioned to form U-shaped pockets adapted to receive said center sills.
7. In combination in a car underframe having spaced center sills and an end sill, a draft arm comprising spaced combined channel and angle-shaped pocket-forming portions adapted to receive portions of said center sills, a portion preserving the alignment of said pocket-forming portions and draft sill portions, and means securely connecting portions of said center sills to said draft arm.
8. In combination in a car underframe having spaced center sills, a draft arm comprising spaced longitudinally extending pocket-forming portions adapted to receive end portions of the center sills, a portion preserving the given locations of said pocket-forming portions and draft sill portions extending below said pocket-forming portions, parts of the latter and said pocket location-preserving portion forming another pocket, and a reinforcement for said center sills upon which they rest extending into the last mentioned pocket and being secured to said draft arm.
9. In combination in a car underframe having spaced center sills, a draft arm comprising spaced longitudinally extending pocket-forming portions in which said center sills lie, and a portion intermediate said pocket-forming portions uniting the same and co-operating therewith to form another pocket, portions of said pocket-forming portions projecting below the normal bottoms of the pockets and being fashioned into Z-shaped draft sills, a reinforcement connected with the center sills extending into the last mentioned pocket and being secured to the inner end of said draft arm, and means connecting said center sills and draft arms.
10. In a car underframe having spaced center sills, a draft arm provided with a rear portion shaped to have a series of alternately reversing channeled portions the outside channeled portions thereof embracing said center sills, said draft arm having a forward portion in which said outside channeled portions progress forwardly and change to depending flanged draft sills.
11. In combination in a car underframe having spaced center sills and an end sill, a draft arm provided with a rear portion shaped to have a series of longitudinally arranged alternately reversed channeled portions, the outer of which portions embrace said center sills, said draft arm having a forward portion in which said outer chan-
- neled portions progress forwardly and change to depending Z-shaped draft sills extending under the end sill, and means connecting said draft sills to said end sill.
12. In an underframe having spaced center sills, a one-piece draft arm provided with a rear portion shaped to form a series of longitudinally arranged alternately reversed channeled portions some of which are spaced to embrace said center sills, said draft arm having a forward portion in which said center sill-embracing channeled portions continue in part and flanged draft sill portions extending downward from the parts of said channeled portions in the forward draft arm portion.
13. In combination in a car underframe having spaced center sills, a draft arm having spaced longitudinal channeled seats in which end portions of the center sills lie and a channeled pocket-forming portion intermediate said seats, angular center-sill reinforcing members, portions of which underlie the center sills and which are clamped to said sills, said reinforcing members having end portions projecting into said draft arm channeled pocket-forming portion, and means rigidly uniting said reinforcing members and draft arm.
14. In combination in an underframe having spaced center sills, a draft arm having transversely spaced seats for end portions of the center sills and an inverted U-shaped portion intermediate said seats, center sill-reinforcing members lapping said inverted U-shaped draft arm portion and extending toward the opposite end of the underframe, said members underlying portions of and being clamped to said sills and being conformed to said inverted U-shaped draft arm portion, means uniting said reinforcing members, and means rigidly combining the latter and said draft arm.
15. In combination in a car underframe having spaced center sills, a draft arm retaining portions of the center sills and provided with a reinforcement-receiving portion, a center sill reinforcement comprising spaced Z-bars each having an upper flange directed toward that of the adjacent Z-bar and a plate connected to and connecting said upper flanges, said draft arm reinforcement-receiving portion and a portion of said center sill reinforcement lapping each other and being connected together in their lapping portions, and means clamping said Z-bars to said center sills.
16. In combination in a car underframe having an end sill, a bolster and spaced center sills, a draft arm extending from the end sill to beyond the bolster and comprising portions embracing opposite sides of each center sill rearwardly of the bolster and one side and a bottom portion thereof forwardly of the bolster, a portion preserving

the relative positions of said center sill-embracing portions, and depending draft sill portions, means connecting the center sills and draft arm, and means connecting the latter to said end sill and bolster.

17. In combination in a car underframe having center sills and bolsters, draft arms passing from one side of the bolsters to the other side thereof and having Z-shaped

10 draft-lug-bearing side walls merging with spaced U-shaped center-sill-receiving pocket portions, said draft arms being interlocked with the center sills and abutment means interlocking said draft arms with said bol-

15 sters.

18. In combination in a car underframe having spaced center sills, a reinforcement for said underframe comprising channelled draft arms at opposite ends of the under-
20 frame and a channelled intermediate reinforcement secured to the center sills and to said draft arms connecting the latter, the center sills, draft arms and intermediate draft arm-connecting reinforcement having longitudinally lapping mutually fitting portions, and means suitably connecting the center sills and draft arms.

19. In combination in a car underframe

having spaced center sills, a reinforcement for said underframe comprising draft arms 30 at opposite ends of the underframe provided with U-shaped pockets receiving the center sills, and a sill reinforcement intermediate said draft arms connecting the same and extending under the center sills secured thereto and fitted to a plurality of sides of the sills and said draft arms.

20. In combination in a car underframe having spaced center sills, a reinforcement for said underframe comprising draft arms 35 at opposite ends of the underframe provided with angular seat portions receiving the center sills and a sill reinforcement intermediate said draft arms lapping each draft arm, extending under the center sills and fitted to a plurality of sides of the draft-arms and sills, and means connecting said sill reinforcement to the sills and draft arms.

In witness wherof I have hereunto set 40
my hand in the presence of two witnesses.
